UNITED STATES PATENT OFFICE.

THOMAS SOWERBY, OF VANCOUVER, BRITISH COLUMBIA, CANADA.

FARE-BOX.

1,115,606.

Specification of Letters Patent.

Patented Nov. 3, 1914.

Application filed December 10, 1913. Serial No. 805,764.

To all whom it may concern:

Be it known that I, THOMAS SOWERBY, a citizen of the Dominion of Canada, residing at Vancouver, in the Province of British Columbia, Canada, have invented certain new and useful Improvements in Fare-Boxes, of which the following is a specification.

This invention relates to an improvement 10 in fare boxes of that class used by street car conductors to receive either fare tickets or coins, and the improvement is directed to a provision to indicate whether the fare box has been tampered with in an endeavor to 15 abstract the coins through the slit through which they were introduced into the box. The entering slit of these fare boxes is provided with a series of teeth pivotally mounted on each side. These teeth are interprojected 20 across the width of the slit and will yield downward to permit a fare being introduced but are designed to exercise a grip thereon and prevent withdrawal. With the use of suitable appliances, coins 25 can be abstracted through the slit and this abstraction is frequently practised. My effort has therefore been to so mount the teeth that if any effort is made to abstract fares, the teeth will yield backward from 30 the slit and cannot be restored until the box has been taken apart which can only be done by a properly authorized person. The means whereby this result is attained is particularly set forth in the following specification, reference being made to the drawings by which it is accompanied, wherein—

Figure 1 is a vertical section through the fare box complete. Fig. 2 is a side elevation and part section of the guard device. 40 Fig. 3 is a plan of the same, and Figs. 4 and 5 show in the engaged and disengaged position the telltale check of the pins on which the teeth are mounted which is the particular subject of this application.

45 In the drawing 2 represents the fare box proper and 3 the cover of the same which is provided with an elongated slit 4 through which the fares are introduced into the box.

Within the upper part of the box immediately under the cover 3 is a guard box 5 within which is a provision to be described later, to prevent abstraction of the fares, and below this guard box and between it and the cash receptacle 10 of the fare box is

a viewing chamber 6 having a bottom 8, 55 which is tiltable about its middle on an axis 9 by means of a push button 11, which the conductor can operate by his thumb while holding the box by its handle 12, or while the box is in the receptacle provided 60 for it in the vestibule of a pay-as-you-enter car. This viewing chamber has a glass 7 in one or both sides through which a fare, which has been dropped into the box, can be viewed by the conductor before he tilts 65 the bottom 8 to deliver it into the cash receptacle 10.

In the upper part of the guard box 5 and immediately below the cover 3 a series of chisel pointed teeth 16 are mounted on a 70 wire pin 15 on each side of the aperture 4 of the cover. The points of these teeth are interprojected as shown in Fig. 3, across the aperture 4 and the teeth are maintained at the proper distance apart and supported 75 laterally by frames 18 and 19, which are slotted to receive the teeth, a frame 18 extending across the width of the guard box at the top on each side of the slit 4, and those 19 extending down the depth of the 80 box in alinement with the aperture 4 on each side.

The slots in the supporting frames 19 also serve to limit the upward movement of the points of the teeth and check them at a 85 slight downward retaining angle, see Fig. 1.

The teeth 16 are held lightly against the limiting check of the member 19 by light springs 28 acting through the intervention of levers 25, one for each tooth, the ends of 90 which levers bear on the undersides of the teeth close to their pivot pins 15.

The construction as described so far is practically the same as in existing fare boxes, but the ends of the pins 15, instead 95 of being secured in the sides of the guard box 5, as is the present custom in fare boxes of this class, are supported in elongated apertures 20 in the sides of guard-box 5.

The pins 15 are normally retained at the 100 inner limit of their movement, see Fig. 4, by the ends of a spring 21 secured at 30 to the sides of the box 5 at each end of each pin 15. The ends of the springs 21 are bent to engage and hold the ends of the pins 15 in their 105 interprojected position, but if force be applied to move the pins outward from one another, the ends of the springs will yield to

allow the pins to pass but will spring together again, as shown in Fig. 5, to retain the pins 15 at the outer limit of their movement in which position the teeth 16 are inoperative.

The pins 15 bear against the underside of the horizontally disposed support frames 18 so that the pins are well supported throughout their length against any bending tendency upward, while they are free to move backward if such undue pressure is imposed upon them as will overcome the hold exerted on their ends by the ends of the springs 21.

With a fare box so constructed, although it does not prevent the abstraction of fares through the entrance slit, if any attempt is made to withdraw a fare therefrom, the teeth are moved back in the manner described and are rendered inoperative, and the fact that the attempt has been made is palpably evidenced when the box is handed into the office at the conclusion of the conductor's shift of service, as the pins 15, when they have been sprung beyond the ends of the spring 21, cannot be restored until the fare box is taken apart.

When a fare box is provided with the tell-tale device hereinbefore described, it may be simplified in its construction otherwise: In existing fare boxes the teeth 16 being an insufficient safeguard against abstraction of fares have various supplementary provisions to further prevent such, which supplementary devices are entirely dispensed with in the fare box, which is the subject of this application.

No claim for novelty is made on the retaining teeth 16, or on the general means for mounting the same, or for holding them up to their work, as such are known to be in common use, but

I claim as new and desire the protection of Letters Patent in the following features:

1. In a fare box having an entranced aperture, a series of teeth arranged on each side below the entrance aperture to prevent withdrawal of a fare when once inserted, of means co-operative with the teeth for rendering the same inoperative for their designed

object when attempt is made to forcibly abstract a fare.

2. In a fare box having an entranced aperture, a series of teeth arranged on each side below the entrance aperture to prevent withdrawal of a fare when once inserted, of means co-operative with the teeth for spreading apart the pivot pins on which they are mounted when pressure is applied to abstract a fare from the box, and means checking the restoration of the pins to their normal position.

3. In a fare box having an entranced aperture, a series of teeth arranged on each side below the entrance aperture and designed to prevent withdrawal of a fare when once inserted said teeth being loosely mounted on of the pins at the inner limit of the apertures means for supporting the ends of said pins said means comprising side plates having elongated apertures for the reception of the ends of the pins which pins project through the aperture, and means for holding the ends of the pins at the inner limit of the apertures and for preventing the return to such position when once they have been moved to the other end of the apertures.

4. In a fare box having an entranced aperture, a series of teeth arranged loosely on a common pin on each side below the entrance aperture to prevent withdrawal of a fare when once inserted, a guard frame within which these teeth are carried said frame having side plates with elongated apertures in which the ends of the pins are mounted, and a spring secured to each side plate the ends of which spring are bent to retain the ends of the pins against the inner ends of the elongated apertures the ends of said spring being such as will engage and prevent return of the pins to the inner end when they have once been moved to the outer end.

In testimony whereof I affix my signature in presence of two witnesses.

THOMAS SOWERBY.
